FLUSHING DEVICE

Filed July 28, 1932

UNITED STATES PATENT OFFICE

2,015,003

FLUSHING DEVICE

Charles Watkins Brown, San Diego, Calif.

Application July 28, 1932, Serial No. 625,417

11 Claims. (Cl. 137—93)

This invention relates to no-tank flush valve mechanisms for closets and the like and has particular relation to such a valve mechanism which will deliver a plurality of quantities of water, 5 selectively to the closet for flushing.

In times of drought and in cities and towns where there is a limited water supply, it is necessary to effect every possible economy in the use of water. Investigation of the uses of water has 10 shown that one of the greatest uses of water is for closet flushing purposes. It has also been determined, by experiment, that much of the water used in closet flushing is in excess of the needs and consequently could be saved.

15 In many of the closet flushing devices in common use, the construction is such that not only is more than a sufficient amount of water delivered to perform the flushing operation, but the operator has no means of controlling the amount 20 of water which is to be used. In these devices the amount used is always the same and is more than necessary in more than half the times operated.

The primary object of this invention is the provision of an improved closet flushing device.

25 Another object of the invention is the provision of an improved closet flushing device capable of delivering any one of a plurality of predetermined amounts of water to the closet, under the control 30 of a single operating means.

A further object of the invention is the provision of an improved closet flushing device capable of delivering any one of a plurality of predetermined amounts of water to the closet and having 35 a chamber with a movable wall for operating the flush valve and a plurality of control valves for selectively operating the flush valve by varying the amount of flush water permitted to pass between opening and closing thereof.

40 Other and further objects of the invention will be apparent to those skilled in the art, from a reading of the complete specification and claims.

Referring to the drawing where I have illustrated an embodiment of the invention,

45 Figure 1 is an irregular cross section approximating on the line 1—1 of Figure 2.

Figure 2 is a cross sectional view on the line 2—2 of Figure 3.

Figure 3 is a front view of the whole device.

50 Figures 4 and 5 are fragmental views illustrating the action of the adjustable valves in the refilling operation.

The same reference characters refer to the same or similar parts throughout the specification and drawing.

Referring particularly to Figures 1 and 2, 10 designates the main body portion of a no-tank flush device having an inlet connection 11 and an outlet connection 12.

An important feature of this invention is the provision of a single flush valve having a chamber with a movable wall connected to the valve to move it in its opening and closing action. The upper portion of the main body portion is provided with a chamber 13 having a movable wall 10 in the form of a piston 14 which is connected by a valve stem 15 to a valve 16. The valve 16 is normally seated on a valve seat 17 in the main body member 10.

Between the piston 14 and the valve 16 and at 15 one side, is an inlet opening 18 which extends to the inlet connection 11 already described. Below the valve 16 is an opening which extends to and through the outlet connection 12, already described.

20 Above the main body member 10 are located the control devices. These control devices provide control mechanism for quickly causing the valve 16 to open, and to cause the same to close and stop the flushing operation, after a sufficient 25 and selective predetermined amount of water has been released. In the present modification, is illustrated a control mechanism which will release either one of two different amounts of water, depending upon whether the user desires a 30 larger or smaller amount of water released. It is to be noted also that in the modification illustrated, either of these amounts of water may be released by the same manual means.

35 In carrying out my invention as illustrated, I provide a head casting 19 which in use is suitably secured to the main body member 10 by any suitable means such as bolts or screws (not shown). Between the main body member 10 and the head casting 19 is a suitable gasket 20.

40 The head casting 19 is provided with an irregular recess 21 at its forward side, to provide space for certain parts of the control mechanism to be described.

45 Within the recess 21 is mounted a bellcrank lever 22 on the pivot 23. The pivot 23 comprises a shank 23^a (Fig. 1) which extends through the bottom wall of the head 19 and is provided with a head. On the upper side of the bottom wall of 50 the head casting 19 and about the shank 23^a is threaded a nut 23^b which holds the pivot 23 in proper position.

The bell-crank lever 22 is provided on its outer extension with an operating handle 24. Within 55

the recess and extending sidewise from the pivot 23 are the double bifurcated arm 22^c, 22^d.

At the rear side of the head casting 19, I provide a boring 25. This boring extends full size 5 nearly to the recess 21 and then by a smaller opening 25^a is connected to the recess 21. Within this boring 25 is placed the control valve, the operation of which effects the opening of the flush valve 16.

10 A cylindrical holder or casing 26 is made sufficiently large to fit snugly, but not too tightly in the boring 25. This casing 26 is provided with a suitable valve seat 27 for a valve 28. The valve 28 has a valve stem 29 on the end of which is an 15 eye 30. The opening 25^a is of a sufficient size to permit passage of the eye 30 during the assembling operation. The inner or forward end of the casing 26 is provided with interior threads in which are threaded two rings 31 between which 20 is a packing 32. The stem 29 is kept tight against water leakage by this packing 32. A suitable spring 33 normally tends to keep the valve 28 seated on its seat 27.

25 The outer or rear end of the casing 25 is retained in place by a plug member 34 which presses on a gasket 35 which rests against the end of the casing 26. The casing 26 is provided with an opening 26^a which connects with a passage 19^a in the head casting 19. This latter opening opens 30 into the cylinder chamber 13.

35 On the opposite side of the valve 28 is an opening 26^b in the wall of the casing 26. This opening 26^b opens into the opening 19^b, of the head casting, which latter opens into a passage 10^a in the main body member 10. This latter opening 10^a extends to the opening in the outlet connection 12. At this point, attention is called to the fact that if the valve 28 is opened and pressure is applied to the bottom of the piston 14, the 40 contents of the cylinder will empty through the passage 10^a to the outlet connection 12.

45 Connected to the eye 30 are two links 36 and 37. Each of these links 36, 37 has a loose connection to the bell crank lever 22 and on opposite sides of the pivot 23. The links 36, 37 are of such a length that when the parts are in normal positions, the connections to the bell crank lever 22 will be at the outer ends of the respective slots 36^a, 37^a. The slots 36^a, 37^a are of sufficient length 50 so as to permit the full throw of the lever 22 without the respective connections reaching opposite respective slot ends.

55 On opposite sides of the rear portion of the recess 22 are two borings 38, 39 made from the forward end.

60 These borings are made dead-end and of such a size as to receive the control valve means which with cooperating parts control the closing of the flush valve and consequently the amount of water provided for flushing.

65 Within the borings 38, 39 are placed valve casings 40, 41. These casings 40, 41 have but one open end which is forward. A countersunk packing 42 and threaded ring 43 seat provides a tight joint for the valve stem 44 of the valve 45 and the valve stem 46 of the valve 47.

70 On the end of the valve stem 46 are heads 48, 48', and on the end of the valve stem 44 are heads 49, 49'.

75 The double bifurcated arms 22^c, 22^d, engage respectively the heads 49, 49', and 48, 48', just described. The inner bifurcated portion, of each of the double arms 22^c, 22^d, is split and straddles the valve stem 44 or 46 as the case may be. It will be observed that the movement of the bell

crank lever 22 in either direction as far as possible will move one valve 45 or 47 back and will pull the other valve 47 or 45 forward for a purpose to be described.

The casings 40, 41, are provided with respective 5 openings 40^a, 41^a, which register with corresponding openings as shown at 19^d, 19^e, in Figures 1 and 5. These openings 40^a, 41^a are on first one side, then the other of the valves 47 and 45, depending upon which way the handle 24 was last 10 moved.

The casings 40, 41 are provided also with other openings in their respective side walls. These openings I have designated 40^b, 41^b, respectively. The openings 40^b and 41^b register with openings 15 19^d, 19^e.

Adjustable valves 50, 51 are screw threadedly held in the head casting 19. These adjustable valves 50, 51 have openings 50^a, 51^a therethrough as shown in Figures 1, 4 and 5. By shifting these 20 valves angularly with a screw driver or other suitable instrument, the amount of water which will pass in a given time for a given pressure, may be controlled and varied to increase or decrease the amount of water which will pass the 25 valve 16 during one operation. The openings 50^a, 51^a connect to passages 10^b, 10^c as illustrated in Figures 1, 4 and 5. The lower ends of these 30 passages 10^c, 10^d connect to the inlet opening 13 and receive their water supply therefrom. 30

I will now describe the operation of my invention.

Let us assume the parts to be in the positions illustrated in Figures 1 and 2. The chamber 13 above the piston is filled with water at the service pressure. The inlet connection 18, which is connected to the water supply, has kept the space below the piston 14 and the passage 10^c, full of water at the service pressure. The piston 14 is therefore balanced. The valve 16 is on its seat 17 40 and is held there by the water pressure. It will be noted that the valve 16 is of smaller cross section than the piston 14.

45 With the positions of the piston and valve as above set forth, the initial positions of the valves 45 and 47 are immaterial. However, in normal operation one valve 45, for example, will always be on the opposite corresponding side of its duct outlet openings 41^b, 40^b from the position of the other. 50

This is brought about by the fact that whenever the crank arm 22 is moved by the handle 24, the bifurcated extensions 22^c, 22^d, move in opposite directions with a consequent movement of the valves 45 and 47 in opposite directions. 55

At the time of installation, the valves 50 and 51 are secured at different adjustments so that the water pressure from passages 10^b and 10^c may fill the cylinder at different speeds due to the different restrictive settings of the valves 50 and 51. One valve as for example the valve 50, is adjusted so that while sufficient water is passing its opening 50^a, to fill the chamber above the piston 14, and consequently, to close the valve 16, enough water will have passed the valve 16 60 to have caused a small flushing of the toilet. Likewise the valve 51 would be set at the time of installation, so that passage to the chamber 13 through the valve 51 than through the valve 50. This in time results in a longer closing operation for the valve 16 and a greater passage 65 of water for the flushing operation. It will thus be seen that by changing the adjustment of the 70 75

valves 50 and 51, the amount of water for the flushing operations can be controlled.

Let us assume the handle 24 to be moved to the right in Fig. 3 which in Fig. 2 would be 5 counterclockwise. As the bifurcated extensions 22^c, 22^d are moved, the valve stem heads 49 and 48' will be respectively, pushed inwardly and pulled outwardly.

These two movements move the valves 45 and 10 47 so that they are on opposite sides of their respectively controlled outlet openings 41^b, 40^b.

Simultaneously with the movement of the valves 45, 47, there is tension placed in the rod 36. This opens the valve 28 by pulling on its 15 stem 29, compressing the spring 33. As soon as the valve 28 opens, the pressure within the chamber 13 is released through the passage 19^a, into the chamber within the cylindrical valve casing 26, past the open valve 28, out through the 20 passage 19^b, through the passage 10^a and into the closet flush chamber (not shown), below the outlet 12. The pressure of the water line within the inlet 18, forces the piston 14 upwardly. Being of a greater cross section than the valve 16, the 25 pressure on the upper surface of the valve 16 is overcome and the latter is opened to permit of the start of the flushing operation. The sizes of the passages 10^a, 19^b, the valve 28, the piston 14 and the valve 16 are so related to each other 30 that with the pressure used in the water supply, the chamber 13 will be quickly emptied.

Upon release of the handle 24, the spring 33 expands thus closing the valve 28 and by pulling on the valve stem 29, pulls the link 36 to return the crank arm 22 and the handle 24 to its initial 35 position. It might be here noted that whether the handle 24 is moved to right or left, one of the links 36, 37 will be caused to operate to open the valve 28, the link in which tension is applied 40 being the one to function.

During this operation the other link because of the slotted ends 36^a, 37^a simply moves idly. It will also be noted that there is room for the bifurcated ends of the extensions 22^c, 22^d to return to their initial positions without changing the maximum position of the valve caused by the positive operation of the handle 24.

After the return of the valve 28 to its seat with the consequent end of the egress of water 50 from the chamber 13, the latter immediately begins to fill through the inlet 18, the passage 10^c, the valve opening 51^a, the passage 19^c, the passage within the casing 41, the passage 41^a and the passage 19^c into the chamber 13. As long 55 as the chamber 13 is filling, the piston 14 will be moving downwardly and the valve 16 will be open. During the period when the valve 16 is open, the flushing operation will continue to take place. As the valve 16 completely closes, all parts 60 and the water resume a static condition.

When the handle 24 is operated in the opposite direction, a similar operation takes place with the water which refills the chamber 13 being controlled by the valve 50 and the valve 47, the time 65 of closing being in accordance with the setting of the valve 50.

It is thus seen that a plurality of selective amounts of water are at the disposal of the operator which permits of the correct amount of water being used without wasting the water as is necessary in using a type of flushing mechanism which must always be set for a maximum amount of water when perhaps half of the times a much smaller amount is needed.

75 While I have illustrated and described one em-

bodiment of my invention, I desire to have it understood that the illustration and description are merely exemplary and that modifications and changes may be made without departing from the spirit of the invention and within the scope of 5 the appended claims.

Having described my invention what I claim and desire to secure by Letters Patent is:—

1. A no-tank flushing device comprising a single flush valve, selectively operated control devices for operating the valve to deliver one of a plurality of selective predetermined quantities of water and manually operable means for selectively operating the control devices.

2. A no-tank flushing device comprising a single flush valve, selectively operated control means for controlling the operation of the flush valve to deliver one of a plurality of selective predetermined quantities of water and manually operable means for selectively operating the control valve 15

20 means.

3. A no-tank flushing device comprising a single flush valve, a plurality of selectively operated control valves for controlling the operation of the flush valve to deliver one of a plurality of selective predetermined quantities of water and manually operable means for selectively operating the control valves.

4. A no-tank flushing device comprising a single flush valve, a plurality of selectively operated control valves for controlling the operation of the flush valve to deliver one of a plurality of selective predetermined quantities of water and a single manually operable means for selectively operating the control valves.

35 5. A no-tank flushing device comprising a single flush valve, a plurality of control valves for controlling the operation of the flush valve to deliver one of a plurality of selective predetermined quantities of water, a manually controlled 40 lever and connections from the lever to the control valves to operate them selectively by different movements of the manually controlled lever.

6. A no-tank flushing device comprising a single flush valve, a piston connected to the flush 45 valve for moving the latter, a cylinder for the piston, a control valve for controlling the egress of water from the cylinder and a plurality of control valve means for controlling the ingress of water to the cylinder to at will selectively vary 50 the time of closing of the flush valve and manually operable means for selectively operating the control valve and control valve means.

7. A no-tank flushing device comprising a single flush valve, a piston connected to the flush 55 valve for moving the latter, a cylinder for the piston, a control valve for controlling the egress of water from the cylinder, control valve means for controlling the ingress of water to the cylinder to selectively vary the time of closing of the flush valve, and manually operable means for operating the control valve and control valve means, connections between the control valve and the manually operable means to cause the operation of the control valve whenever the manually operable means is operated and means under selective control of the manually operable means to predeterminedly control the speed of closing of the flush valve.

8. A no-tank flushing device comprising a single flush valve, a piston connected to the flush valve for moving the latter, a cylinder for the piston, a control valve for controlling the egress of water from the cylinder and control valve means for controlling the ingress of water to the 75

cylinder to selectively vary the time of closing of the flush valve and a single manually operable means having a plurality of movements to operate the control valve means selectively and connections from the manually operable means to the control valve to operate the latter when the former is moved.

- 5 9. A no-tank flushing device comprising a single flush valve, a water chamber having a movable wall connected to the flush valve for moving the latter, and means for controlling the movable wall, said controlling means including a valve for controlling the egress of fluid from the chamber and moving the movable wall to open the flush valve, and a plurality of selectively controlled valves and connections of different flow capacities to control the ingress of fluid to the chamber to move the movable wall in the opposite direction to close the flush valve and predeterminedly control the amount of water passing the flush valve.
- 10 10. A no-tank flushing device comprising a

single flush valve, a water chamber having a movable wall connected to the flush valve for moving the latter and means for controlling the movement of the movable wall, said controlling means including a valve for draining water from the chamber to cause opening of the flush valve and a plurality of selectively controlled valves and connections of different flow capacities to refill the chamber.

15 11. A no-tank flushing device comprising a single flush valve, a piston connected to the flush valve for moving the latter, a cylinder for the piston, and means for controlling the opening and closing of the flush valve by operation of the piston, said controlling means including a valve for draining water away from one side of the piston to open the flush valve and a plurality of selectively controlled valves having connections, of different flow capacities, to the cylinder, to close the flush valve.
